UNITED STATES PATENT OFFICE

2,371,321

WASTE-COLLECTING SYSTEM FOR
ROTARY CUTTERSErnest W. Stacey, Beverly, Mass., assignor to
United Shoe Machinery Corporation, Flemington, N. J., a corporation of New JerseyOriginal application August 27, 1941, Serial No.
408,468. Divided and this application September
4, 1943, Serial No. 501,275

8 Claims. (Cl. 12—1)

This invention relates to means whereby the chips and other waste from a rotary cutter, as, for example, those employed for rounding or forming to a pattern the soles of shoes, are collected and removed from the vicinity of the cutter. It is of particular utility in connection with such a sole-rounding machine as that disclosed in the application for Letters Patent filed in my name in the United States Patent Office on August 27, 1941, and bearing the Serial No. 408,468. Of that case, the present application is a division.

In machines of the character above mentioned to carry the work through a path which offers an approximation of the form to be imparted to it by a rotary cutter, said work, as a sole-blank or a stack of such blanks, is given a compound movement of oscillation and rotation. The blank thus has a movement of translation which shifts it through a considerable distance, and it is so turned that the varying angle at which it is presented to the cutter causes the chips produced to be thrown off in different directions. This makes it difficult to associate with the work efficient waste-collecting means which will not interfere with the movement, and also to provide such means which will fully retain the differently projected particles. My invention has as an object the provision of a system which will properly dispose of the waste produced by the cutter in all positions of the work, and which will still permit the free travel of said work past the cutter. To this end, I combine with an oscillatory and rotary work-holder, as one for shoe-soles, and a rotary cutter to which the holder presents the work, an exhaust-conduit into the mouth of which said work is movable as it receives the action of the cutter. The chips and dust thrown off by the cutter are thus subjected directly to the force of the exhaust, but without interference with the movement of the work, because of lateral expansion of the conduit-mouth. A baffle preferably assists in the retention of the waste, it being furnished by a wall which divides from the main exhaust-conduit an auxiliary conduit, through which is removed material which may pass the baffle. The collection of the waste may, therefore, be practically complete.

A particular embodiment of the invention is illustrated in the accompanying drawings, in which

Fig. 1 is a partial vertical section, taken in a plane from front to rear of a sole-rounding machine in which my improved collecting system is included, this section passing through the for-

ward portion of the cutter-carrying arm and being viewed from the right of the machine;

Fig. 2 is a broken side elevation, also taken from the right and especially showing the mounting of the exhaust-conduit; and

Fig. 3 is an enlarged horizontal section on the line III—III of Fig. 2, and including the entire exhaust-conduit.

In the sole-rounding machine of the previously mentioned application, there is a frame 10, upon which, about a vertical tubular shaft 12, a work-carrier 14 is mounted to oscillate under the influence of gearing A and connected mechanism B. Rotatable in lower and upper arms 16 and 18, respectively, of the carrier 14 are vertical shafts 20 and 22. The shaft 20 is driven through the gearing A, and has mounted upon its upper extremity a pattern 24. The shaft 22 carries at its lower extremity a clamp 25, driven from the gearing A through the shaft 12 and gearing C in synchronism with the pattern. Through a rod 26 within the shaft 12 and through an intermediate lever 28, the clamp may be lowered or raised to secure or free for removal one or more sole-blanks S, or other work-pieces. The compound movement of oscillation and rotation of the clamped work is of such a character, that any point at the periphery of the blank is moved through a path which roughly corresponds to the contour of the pattern 24.

Rising from the frame 10, at the right of the work-carrier 14, is a tubular post 30, about which is mounted to oscillate a carrier-arm 32, in the outer end of which a vertical shaft 34 is rotatable, it having fixed upon it a toothed rounding cutter 36. The shaft and cutter are constantly driven during the operation of the machine through gearing D from a shaft 38 rising through the post 30. The carrier-arm may be oscillated about the post to shift the cutter between the inactive position of Fig. 1, which permits the application to and removal from the pattern 24 and clamp 25 of the work, and the active position of Fig. 3, in which the rounding of the work may take place. This is effected under the control of the operator by mechanism indicated at E. This mechanism is joined to the carrier-arm by a link 40. The approach of the cutter to the work and the precise contour which it imparts thereto are determined by contact with the periphery of the pattern 24 of a gage-roll 42 mounted upon the carrier-arm.

In the action of the cutter upon the work, a considerable quantity of chips and dust are produced, which must be disposed of. For this pur-

pose, the arm 32 is tubular to furnish an exhaust-conduit having a main passage 43. It is shown as having flat upper and lower walls 44, 44, and tapering inwardly at the sides, with an increase in the velocity of the air-current, from a wide laterally expanded mouth 46 to a passage 47, which curves about the post 30. The passage 47 opens at 48 through a segment 50 upon the arm 32, this bearing closely against a complementary segment 52 about the opening of a conduit 54, which may be connected to the factory-exhaust system. The mouth 46 extends from a side wall 56 of the conduit, close to which the cutter 36 is carried, to the opposite shorter side wall 58 curved inwardly and rearwardly to the passage 47. The width of the mouth is such that in all positions of the oscillating and turning pattern, clamp and work-pieces, these may move across and into the conduit without interference. Yet for the varied angles at which the work is presented to the cutter, the waste removed from the blank is projected directly into the conduit, remaining under the full influence of the exhaust.

The conduit-wall 56 extends as close to the cutter 36 at 57 and as far forward as possible, while remaining free from contact with the turning work, to retain the waste carried by said cutter in the direction of its rotation. Further, to prevent the waste from escaping past the wall-portion 57, there extends along the wall 56 an inner wall 60 joined to the upper and lower walls 44 and forming an auxiliary exhaust-passage 62 joining the inner passage 47 at 64. The outer end of the wall 60, at 66, lies in close proximity to the periphery of the cutter, which turns from the work inwardly toward it. Consequently, this wall serves as a baffle, the greater part of the waste thrown in this direction coming in contact with it and being retained within the main passage 43 to be disposed of through the passage 47. Whatever passes the baffle, comes under the influence of the exhaust through the narrow auxiliary passage, into which the air is drawn at a high velocity. This material is, therefore, disposed of through the passages 62 and 54, together with the greater portion of the waste received through the main passage.

Having described my invention, what I claim as new and desire to secure by Letters Patent of the United States is:

1. In combination, an oscillatory and rotary work-holder, a rotatable cutter to which the holder presents the work, and an exhaust-conduit into

the mouth of which said work is movable as it receives the action of the cutter.

2. In combination, an oscillatory arm furnishing an exhaust-conduit tapering inwardly from a laterally expanded mouth, a cutter rotatable upon the arm within the mouth of the conduit, and an oscillatory and rotary work-holder movable into the mouth of the conduit to receive the action of the cutter.

3. In a sole-rounding machine, an oscillatory and rotary sole-holder, an exhaust-conduit having a laterally expanded mouth into which the sole-holder enters and across which it moves, and a cutter rotatable in the conduit to act upon a sole in the holder.

4. In combination, an exhaust-conduit having a wall dividing it into a main exhaust-passage and an auxiliary exhaust-passage, a work-holder movable in the mouth of the conduit, and a cutter to which the holder presents the work, said cutter being situated with its periphery in close proximity to the end of the dividing wall.

5. In combination, an exhaust-conduit having a wall dividing it into a main exhaust-passage and an auxiliary exhaust-passage, a work-holder movable in the mouth of the conduit, and a cutter rotatable within the conduit and to which the holder presents the work, the operating periphery of said cutter turning from the work into the conduit and toward the end of the dividing wall.

6. In combination, a carrier in which are two exhaust-passages, a dividing wall between the passages, furnishing a baffle, a cutter rotatable upon the carrier at the outer end of the baffle, and a movable work-holder co-operating with the cutter.

7. In combination, a carrier furnishing a main exhaust-passage having a laterally expanded mouth and an auxiliary exhaust-passage, a cutter rotatable upon the carrier between the openings of the main and auxiliary passages, and a work-holder co-operating with the cutter and movable in the mouth of the main passage.

8. In a sole-rounding machine, an oscillatory carrier-arm furnishing a main exhaust-passage having a laterally expanded mouth and an auxiliary passage, a cutter rotatable upon the carrier-arm, a baffle between the passages acting to retain waste produced by the cutter in the main passage, and an oscillatory and rotary sole-holder movable in the mouth of the main passage.

ERNEST W. STACEY.
